UNITED STATES PATENT OFFICE.

JOSEPH BIJUR, OF NEW YORK, N. Y., ASSIGNEE TO BIJUR MOTOR LIGHTING COMPANY,
OF NEW YORK, N. Y., A CORPORATION OF NEW YORK.

ELECTRICAL APPARATUS.

1,246,852.

Specification of Letters Patent. Patented Nov. 20, 1917.

Application filed April 28, 1911. Serial No. 623,834.

To all whom it may concern:

Be it known that I, JOSEPH BIJUR, a citizen of the United States, residing at New York, in the county of New York and State 5 of New York, have invented certain new and useful Improvements in Electrical Apparatus, of which the following is a full, clear, and exact description, such as will enable others skilled in the art to which it 10 appertains to make and use the same.

This invention relates to the generation of electric current upon automobiles as for lighting and the like. One of the objects thereof is to provide a practical and efficient 15 electrical system upon an automobile or in any like relation. Another object is to provide in connection with apparatus of the above type a compact, reliable and adaptable drive. Another object is to provide 20 apparatus of the above nature in which the various elements are compactly disposed, and yet formed and positioned for most effective and dependable action. Other objects will be in part obvious and in part 25 pointed out hereinafter.

The invention accordingly consists in the features of construction, combinations of elements and arrangement of parts which will be exemplified in the construction hereinafter set forth, and the scope of the application of which will be indicated in the 30 following claims.

In the accompanying drawings, wherein is shown one of various possible embodiments of this invention,

Figure 1 is a diagrammatic side elevation of an electrical installation for automobiles and associated parts.

Fig. 2 is a sectional view taken on the 40 line X—X of Fig. 3.

Fig. 3 is an end elevation of an electrical generating unit.

Fig. 4 is a side elevation thereof on a smaller scale.

Fig. 5 is a detail elevation of a regulating device.

Fig. 6 is an end view thereof.

Fig. 7 is a sectional view taken substantially along the line Y—Y of Fig. 2.

Fig. 8 is a detail side elevation of a circuit-making device.

Fig. 9 is an end view thereof.

Fig. 10 is a detail plan of a supporting element.

Fig. 11 is a sectional view taken along the 55 line Z—Z of Fig. 10.

Fig. 12 is a side view of a support for brush mechanism.

Fig. 13 is an edge view thereof.

Fig. 14 is a side elevation of brush mechanism. 60

Fig. 15 is a sectional view of parts shown in Fig. 14.

Fig. 16 is a side view of a casing with removable panel and associated parts. 65

Fig. 17 is a sectional view taken along the line A—A of Fig. 16.

Fig. 18 is a side view showing the shape of the field magnet stampings.

Fig. 19 is a detail sectional view of a 70 contact mechanism involved in the regulating device of Fig. 5.

Fig. 20 is a detail view of the contact holder of this mechanism.

Similar reference characters refer to similar parts throughout the several views of the drawings. 75

Referring now to Fig. 1 of the drawings, there is shown an automobile engine 1 provided with shaft 2, fly-wheel 3, spark-plugs 4 and other accessories. Driven from shaft 2, as by the gearing 5, is a short shaft 6 which leads to and drives a magneto 7, the latter generating ignition current for the spark-plugs 4. Driven from a sprocket 8 on shaft 6 by means of the sprocket-chain 9 coacting with a sprocket-wheel 10 is a generating unit which supplies current to the storage-battery 11 and the lamps indicated at 12. 90

Referring now to Fig. 2 of the drawings, in which this generating unit is shown in section, it may be noted that it comprises a supporting bed 13 having inwardly extending ball-bearings 14, in which is journaled a shaft 15, provided with a gear 16 in a casing 17 and having fixed thereon beyond said casing the sprocket-wheel 10, above referred to. 95

Mounted upon this bed is the generator 100 proper which comprises a laminated field magnet 18, having secured thereto at opposite ends the casings 19 and 20. Journaled within the inwardly extending ball-bearings of these casings is the armature 105 shaft 21, having thereon the commutator 22, and armature 23, and carrying a pinion 24 meshing with the gear 16, and inclosed

by the removable casing 17. It may be noted that the generator is formed to fit between the bearings 14 and otherwise interlock with the generator bed and may be secured in position as by a strap 25 removably secured to the bed and tautened in place as by the set-screw 26. These parts are so formed and proportioned that as the two sections are assembled, the pinion 24 will mesh properly with the gear 16, and if any slight adjustment is required, it may be attained by the set-screws 27, threaded into the bed and bearing against the lower surfaces of the casings 19 and 20.

Referring now to field magnet 18, it may be noted that it is built up of a plurality of similar stampings, 28, each of which is substantially of the shape shown in Fig. 18 of the drawings. These several stampings, as well as the casings 19 and 20, are held in position by bolts 29, which are provided with nuts 30 at their ends and with shoulders 31 and adjustable collars 32 to confine the stampings. By the arrangement of the field magnet as shown, the magnetic flux is substantially shunted about the driving shaft 15, thus rendering the field entirely independent of the latter and permitting the use of a metal other than iron or steel for this shaft if desired. Also, the shaft, even if of a non-magnetic material, may be brought into the desired close relation to the armature shaft without cutting into the magnetic circuit or interfering with the magnetic flux.

Upon the pole pieces of the field magnets, which are slightly beveled away from a concentric surface, as at 33, are the magnet windings 34, 35 and 36, these windings being formed substantially concentric with the armature in order to economize space.

Coacting with the commutator 22 are a pair of brushes 37, best shown in Fig. 7 of the drawings, these brushes being slidably mounted in removable holders 38, screwed to the rocker 39, shown in Fig. 12. Pivotedly mounted upon this rocker are the levers 40 which bear at their rounded end portions upon the brushes and which are urged toward the brushes by the spring 41 connected with the rocker at 42. By this simple arrangement the brushes are uniformly urged into contact with the commutator, and yet the levers 40 may be swung over into such position as to permit the coacting springs to hold them away from the brushes, as for purposes of renewal.

Formed in the casing 19, at each side of the commutator, is a removable panel 43, best shown in Figs. 16 and 17 of the drawings. The casing is shaped to provide a flange 44, against which the panel rests, and plates 45, beneath which a pivotally mounted flat spring 46 upon the panel is turned to lock the latter in position and urge it inwardly against the flange. Slight irregu-

larities 47 are preferably formed in plates 45 in order to avoid the chance of the spring 46 jarring out of locking position. These panels are substantially opposite the commutator and afford ready access to the brush mechanism and regulating devices, herein-after described, while completely excluding dust therefrom.

As best shown in Fig. 7 of the drawings, there is provided within casing 19, at one side of the commutator 22, a casing or switchboard 48 upon which are mounted the substantially identical regulating devices 49 and the main switch 50. These regulating devices control the connection in the field circuit of the generator of a resistance element 51 mounted within casing 20, as shown in Fig. 2 of the drawings, the shield 52 being provided to guard the field coils from the heat of this element. The details of the electrical connections for these parts are not shown herein, as they, in themselves, form no part of the present invention.

Recurring to the construction of the regulating devices 49, attention is directed to Figs. 5 and 6 of the drawings. As shown in these figures, there is provided a magnet 53 having a core 54 formed with an enlarged head or end 55. Secured to the opposite end of core 54 is a support 56 bearing an iron member 57 which has pivoted at its free end an armature 58 retracted from core 54 by the adjustable spring 59. Mounted upon the magnet adjacent the head 55 is a brass member 60. Formed upon member 60 is a resilient cross-piece 61 provided with a pin 62 having an enlarged head. A similar pin 63 is mounted in the brass pin 64, with which the armature 58 is provided, as best shown in Fig. 19 of the drawings. Removably slipped beneath the heads of each of these pins is a spring member 65, shaped as indicated in Fig. 20 and provided with a recess 66 to embrace the corresponding pin, as well as openings 67 communicating with slot 68 at each end. Within these openings are inserted the contact members 69, each of which is formed with a shoulder 70. These contact members are inserted within the openings 67 in spring 65, and the latter slipped into position in which it is held by its frictional contact with the parts with which it engages. The contacts are thus readily removable and are yet securely mounted in position and are adapted as the armature vibrates to make and break the circuit at two points. The armature 58 is provided with a counter-weight 71 whereby its action is rendered substantially independent of the effect of vibration and gravity. The distance between the contacts upon member 61 and those upon the armature is adjusted by a screw 72 provided at the free end of the member 60, and it may be noted that the latter member, as well as the con-

tacts thereon are insulated from the armature. By this arrangement there are provided two parallel contacts, so that in the event of one becoming worn or pitted, the other may maintain efficient action of the device, and also the resilient mounting of the contacts affords a rubbing action as they are engaged by the armature which tends to keep them clean and insure a good electrical connection.

10 Referring now to Figs. 8 and 9 of the drawings, there is shown a main switch which governs the electrical connection of the generator with the external circuit. This switch 15 comprises a magnet 73 which may have several windings and is provided with a core having an enlarged head 74. Secured to the opposite end of this core is a supporting member 75 having pivotally connected thereto a balanced armature 76. This armature bears a removable slotted contact 77 coacting with a fixed contact 78, these parts being so insulated and connected as to control connection with the external circuit. 20 The supporting member 75 is secured to a brass piece 79 which holds it in position and spaces it from the supporting wall indicated at 80, and between these parts is positioned an adjustable retracting spring 81 tending 25 to swing the armature away from the core to a distance limited by a brass stop 82 held beneath the magnet core and extending over the armature as at 83.

With reference to such electrical connections as are involved in this invention, it 30 may be noted that each brush 87 is provided with a flexible conductor 84 terminating in a pin 85 which slips within the perforated post 86, as best shown in Figs. 7 and 16 of the drawings. These connections are readily accessible from the removable side openings of the casing 19 and permit the ready renewal of the brushes should such action become necessary. Leading from one of the 35 posts 86 to the switchboard 48 is a conductor 87 and the return connection is through the flexible conductor 88 and pin 89 to a post 90. From the remaining post 86 and the post 90 connections lead to the 40 line as indicated at 91.

In Fig. 16 of the drawings, there is diagrammatically indicated the method of connection from the body of the generator to the switchboard 48, the end casing being 45 partially withdrawn from the field magnet in order to disclose the structure more clearly. The conductors leading from the body of the generator are diagrammatically indicated at 92 and the corresponding conductors leading to the switchboard are shown at 93. These several conductors are provided with the connections shown at 94 which are substantially opposite the openings in the casing 19 and are thus readily 50 accessible upon a panel being removed.

In the use of the apparatus it will be seen that the generating unit will give the desired high speed of the armature with a relatively low speed of the sprocket 8, and hence it is unnecessary to use a large driving sprocket 70 upon the shaft 6 which might be impracticable by reason of the space which it would consume. This driving mechanism is thoroughly protected and the gears may run in oil, and yet the parts, while compactly disposed and securely held, are readily disassembled, as by loosening the set-screw 26 or removing the strap at one end from the bed 13. The field construction is extremely simple and inexpensive, and yet permits such a shaping as to conserve space without a sacrifice of efficiency and gain a self-contained construction. The two end casings are readily removed, if removal should prove necessary, but the side panels permit access 80 to all of the parts which would need inspection or attention under any conditions, and hence removal of the casings is rarely required. The brushes are held in proper position and yet may readily be removed and renewed, and the mounting of the regulating apparatus, as shown, not only protects it against injury by blows or by the entry of foreign matter, but brings it adjacent the brush mechanism, and thus gathers near a 85 single point all of the parts which may need attention. The construction and action of the main switch will be clear from the above description and the mechanical action of the regulating element has already been 90 described.

It will thus be seen that there is provided apparatus of a compact, and yet simple, construction in which the several aims of this invention are achieved.

As many changes could be made in the above construction and many apparently widely different embodiments of this invention could be made without departing from the scope thereof, it is intended that all 105 matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, 110 might be said to fall therebetween.

Having described my invention, what I claim as new and desire to secure by Letters Patent is:

1. In electrical apparatus for motor vehicles, in combination, an electrical generating and regulating device, comprising an armature, field magnets and means for retaining said parts in assembled relation, a 125 casing, means for removably mounting said 130

casing on a part of said generator, automatic electromagnetic regulating means including an automatic cut-out and a voltage regulator located entirely within said removable casing, and secured thereto, said mounting means being operable from the exterior for mounting and for removing said casing with its inclosed parts from the rest of the construction, and detachable means for connecting said regulating means to said generator.

2. Combined electric generating and regulating apparatus comprising a generator body portion having field magnets and an armature mounted therein, driving means at one end for said armature, a commutator at the opposite end of said armature, a separable longitudinal extension at said latter end having a lateral opening opposite said commutator, regulating apparatus for said generator mounted upon and housed by said extension, and releasable connections from said regulating apparatus to the generating apparatus.

3. Combined electric generating and regulating apparatus comprising a generator body portion having a field magnet and armature mounted therein, a bearing for one end of the shaft of said armature, a separable longitudinal extension at the opposite end of said armature, an internal annular shoulder integral with said extension, a bearing in said chamber for the adjacent end of the shaft of said armature, regulating apparatus for said generator mounted upon and housed by said extension, and releasable

connections from said regulating apparatus to the generating apparatus.

4. Combined electric generating and regulating apparatus comprising a generator body portion having a field magnet and an armature mounted therein, a separable longitudinal extension at one end of said body portion, a commutator connected with said armature and extending into said extension, a bearing formed in and supported by said extension within its length, whereby the total length of the apparatus is reduced, and regulating apparatus mounted upon and housed by said extension and releasably connected with the generator.

5. Combined electric generating and regulating apparatus comprising a generator body portion having a field magnet and an armature mounted therein, a bearing at each end of the shaft of said armature, regulating apparatus for said generator, releasable connections between said regulating apparatus and the body of said generator, a commutator, and an integral extension separably secured at one end of said body portion surrounding said commutator, having said regulating apparatus mounted thereupon and housed thereby, supporting one of said bearings and having therein a lateral opening substantially opposite said commutator.

In testimony whereof I affix my signature, in the presence of two witnesses.

JOSEPH BIJUR.
